(57) **CLAIM**

The ornamental design for a tap socket, as shown and described.

DESCRIPTION

FIG. 1 is a front elevational view of the tap socket of the present invention; the rear, left and right side elevational view being substantially identical thereof;

FIG. 2 is a top plan view of the tap socket of FIG. 1; FIG. 3 is a bottom plan view of the tap socket of FIG. 1; and, FIG. 4 is a cross-sectional view of the tap socket taken along line 4—4 of FIG. 2.

The broken lines are for illustrative purpose only and forms no part of the claimed design.
